UNITED STATES PATENT OFFICE

DOROTHY LONG, OF NEW YORK, N. Y., ASSIGNOR TO FRANKLIN SIMON & COMPANY, INC., OF NEW YORK, N. Y., A CORPORATION OF NEW YORK

DESIGN FOR A COAT

Application filed September 26, 1929. Serial No. 32,873. Term of patent 3½ years.

To all whom it may concern:

Be it known that I, DOROTHY LONG, a citizen of the United States, and a resident of the city of New York, borough of Manhattan, in the county of New York and State of New York, have invented the new, original, and ornamental Design for Coat, of which the following is a specification.

Reference is had to the accompanying drawing, forming part thereof, wherein the dominant feature of the design consists in the curved lines shown in the three figures of the drawing which present a peculiar curved ornamentation at the back, curved lines presenting an overlapped effect on the sides, and offset upwardly curved lines at the front.

Figure 1 is a front perspective view of a coat showing my new design, the same being illustrated on a figure indicated by dotted lines;

Figure 2 is a side view of the coat shown in Figure 1, the same being illustrated on a figure indicated;

Figure 3 is a rear view of the coat shown in Figure 1, the same being illustrated on a figure indicated by dotted lines.

I claim:—

The ornamental design for a coat substantially as shown and described.

DOROTHY LONG.
